Filed July 20, 1964, Ser. No. 80,928

Term of patent 7 years

(Cl. D14—3)

Fig. 1.

Fig. 2.

Fig. 3.

Fig. 4.

FIG. 1 is a top plan view of a trailer showing my new design;

FIG. 2 is an elevational view of one side thereof;

FIG. 3 is a front elevational view thereof; and

FIG. 4 is a rear elevational view thereof.

The side not shown is a mirror image of the side shown, except that the undisclosed side does not have a door therein. The dominant features of my design reside in the portions shown in full lines.

I claim:

The ornamental design for a trailer, as shown and described.
